PIPERAZINE DERIVATIVES

Charles F. Geschickter, Lorton, Va., Ebenezer E. Reid, Baltimore, Md., and John S. Pierce and Ying Ho Chen, Richmond, Va., assignors to The Geschickter Fund for Medical Research, Inc., Washington, D.C., a corporation of New York

No Drawing. Filed Oct. 5, 1959, Ser. No. 844,172
6 Claims. (Cl. 260—268)

This invention relates to derivatives of piperazine and this application is a continuation-in-part of our co-pending application, Serial No. 670,654, filed July 9, 1957, now abandoned. More specifically, this invention relates to compounds of the following structure, herein identified as C:

and their non-toxic acid addition salts, where each of A and A' is a member chosen from the group consisting of H and CH₃ and each of B and B' is a member chosen from the group made up of pyrrolidino, piperidino, 2-methyl piperidino, 2,4-dimethyl-piperidino, morpholino and a dialkylamino radical of the structure

where each of R and R' is an alkyl radical containing from one to four carbons. In the individual compound C, A and A' may be the same or may be different; B and B' may be the same or may be different; R and R' may be the same or may be different.

The compounds of structure C are pharmacologically active and are useful in medicine. They are bronchial dilators and are useful in the control of asthma. They have relatively low toxicities.

Also, the compounds of structure C are useful intermediates for the formation of useful methiodies of the structure

These dimethiodides are relaxants of voluntary musculature and can be used to replace curare where muscular relaxation is important.

In the present invention, compounds of structure C were prepared by one of the following general reactions:

(I) A 60

2

The compounds formed in reactions I and II above are special cases of structure C in which B and B' are equivalent. In reactions III and IV, B and B' may be equivalent or may be different.

45 This invention includes the four methods of preparation of compound C, given just above and it also includes the compound C, itself, within the definitions of A, A', B and B', given above, regardless of the method of preparation.

The following reactions were used in the preparation of some of the intermediates used in the present specification:

3

5

10

15

20

30

35

The intermediate formed in reaction 1 above is used in reaction II in the preparation of compound C. The final product in reaction 4 is used for the synthesis of C by the general reaction IV. It is noted in this latter reaction that B and B' may be equivalent or they may be different. The final product in reaction 5 is used for the synthesis of C by reaction III. Also, in this case C may contain groups B and B' which are equivalent or which are different.

In the preparation of compounds of the structure

60

as comprehended by above-identified structure C, the following distilled epihydrinamines were used:

4

Also, crude 3-pyrrolidino-1,2-epoxypropane of the structure

was used.

In the preparation of a compound of structure C by reaction I, the epihydrinamine was caused to react with 40 the piperazine, usually but not always, in 95 percent ethanol solution. In the present disclosure when "ethanol" is used, it is understood to mean ethanol containing approximately 5 percent water, unless otherwise stated. In a few runs, water was added drop-wise at 45 the outset of the synthesis but usually the water in the ethanol sufficed. As discovered later, results seemed to indicate that in certain syntheses side reactions were decreased by carrying out the reaction of the epihydrinamine and secondary amine in the presence of a small 50 amount of aqueous alkali.

In a typical reaction, to a solution of piperazine in ethanol was added slowly two molar quantities of epihydrinamine. The reaction mixture, after standing for several 55 hours at room temperature, was heated for several hours to approximately 60° C. (Note: All temperatures in this specification are on the centigrade scale.)

The preferred method for the synthesis of compounds of the structure

65

is illustrated by reaction IV. The same epihydrinamines which serve for reaction I also serve for reaction IV.

Usually, in the purification of a compound of structure C, the reaction product was dissolved in aqueous hydrochloric acid and the compound C was precipitated as an oil, with alkali. All of the compounds of this structure reported in this specification were purified by vacuum distillation. The boiling points given in the specification are for the purpose of identification only and are not 75 intended to limit the claims.

Since each of the compounds of structure C contains at least two asymmetric carbons, each product of this structure in this specification, obtained by distillation, is likely a mixture of diastereoisomers. Each of the compounds of structure C reported in Table I, with a few exceptions, is a liquid, usually rather viscous, or a low-melting solid. In general, the compounds of structure C derived from trans-2,5-dimethylpiperazine melt higher than the corresponding compounds derived from piperazine, 2-methyl piperazine or cis-2,5-dimethylpiperazine.

A partial separation of diastereoisomers of one of the compounds of structure C is here described. A sample of distilled 1,4-bis[3-(di-n-butylamino)-2-hydroxypropyl]piperazine of the structure

10

which gave an excellent analysis for nitrogen, remained an oil until it was seeded with a crystalline product of the same compound from another run. After standing for a few hours the mass became semi-solid. After standing for about a month the sample was subjected to suction filtration.

The residue in the Buchner funnel was placed on a clay plate to remove as much as possible of the liquid diastereoisomer. After standing on the clay plate for about three days the white solid melted at 54-55°. The

5

including quaternization of one or both of the tertiary amino groups in D. The compounds of structure D usually were so reactive that they underwent self-condensation on standing for a short time at room temperature or even in the refrigerator. Due to this activity, the bisepoxides of structure D usually were used for reaction II, above, very soon after their preparation.

Of the four bisepoxides of structure D, only one, namely

10

25

was isolated as a solid. The other bisepoxides were obtained as gums or viscous oils.

The following examples are given to illustrate specific methods which have been used in the synthesis of compounds of the present invention but are not meant to limit the scope thereof.

EXAMPLE 1

1,4-Bis[3-(Di-n-Propylamino)-2-Hydroxypropyl] Cis-2,5-Dimethylpiperazine

filtrate in the suction flask became quite viscous when cooled to about -10° but did not become a solid.

The original distillate, the solid and the filtrate gave nitrogen analyses as follows:

Calculated for $\text{C}_{26}\text{H}_{56}\text{N}_4\text{O}_2$: Nitrogen, 12.27%.

Nitrogen found, percent

Original distillate	12.27
Solid (M.P. 54-55°)	12.41
Filtrate	12.09

Typical compounds of structure C of the present invention were converted into acid addition salts which such acids as hydrobromic acid, sulfuric acid, phosphoric acid, acetic acid, lactic acid, citric acid and thiadisalicylic acid. Each of the first six acids listed above was found to form a soluble salt with about twenty-five of the amino alcohols of structure C.

In the preparation of a typical compound of the following structure herein identified as D.

epichlorohydrin was caused to react with the piperazine,

and the reaction product was treated with alkali. Usually, the yields were low, likely due to side reactions,

To 190 g. (1.20 mole) of 3-di-n-propylamino)-1,2-epoxypropane was added slowly over a period of one hour 68 g. (0.60 mole) of cis-2,5-dimethylpiperazine dissolved in 100 ml. of ethanol, the temperature being kept below 15°. The reaction mixture was allowed to stand over night at room temperature and was heated on a gently boiling water bath for about 15 hours.

The mixture was cooled and was treated with 1.5 l. of N hydrochloric acid and with 500 ml. of ether. After separation, the aqueous layer was made strongly basic. An oil came to the surface. The oil and aqueous layer were extracted with 500 ml. of ether. One portion of the ether solution, on evaporation in an open container, yielded a solid. Another portion, on evaporation of the ether and vacuum distillation of the residue, yielded 1,4-bis [3-(di-n-propylamino)-2-hydroxypropyl] cis-2,5-dimethylpiperazine, B.P. 199-202° at 0.20 mm.

At various times it was found that products of structure C which were semi-solids originally, on distillation yielded liquids which tended to remain in the liquid state, some remaining in this form for several months or longer. Some samples, on being seeded, readily deposited crystals, some becoming solid in appearance.

Compound E has been used effectively clinically, in the control of asthma, in over one hundred cases. The dosage usually is 50 mg. This compound is given orally, as the free base, dissolved in sesame oil and in a capsule or as the hydrochloride, dissolved in water. Also, it is given by intramuscular injection as the hydrochloride, in sterile aqueous solution.

The acute toxicity of the compounds of structure C of the present specification, when tested in the rat, usually is between LD₅₀=100 mg./kg. and LD₅₀=300 mg./kg. The acute toxicity of compound E in the rat is LD₅₀=400 mg./kg.

The acute toxicities in the rat of a few compounds very closely related in structure to E are given below:

	LL 50 Mg./Kg.
$(CH_3CH_2CH_2)_2NCH_2CHOHCH_2N$ (CH ₂ CH ₂ CH ₃) ₂ trans	250
$(CH_3CH_2CH_2)_2NCH_2CHOHCH_2N$ (CH ₂ CH ₂ CH ₃) ₂ cis	300
$(CH_3CH_2CH_2)_2NCH_2CHOHCH_2N$ (CH ₂ CH ₂ CH ₂ CH ₃) ₂ cis	200
$(CH_3CH_2CH_2)_2NCH_2CHOHCH_2N$ (CH ₂ CH ₂ CH ₂ CH ₃) ₂	275

Each of the four compounds above, as well as compound E, has been used to relax muscle spasm in arthritics, in sprained backs and for muscular spasm in the gastro-

amino-2-hydroxypropyl] cis-2,5-dimethylpiperazine, B.P. 184-186° at 0.55 mm.

intestinal tract. The results were good. Each of these four compounds proved effective in relieving asthma.

EXAMPLE 2

1,4-Bis [3-(Diethylamino)-2-Hydroxypropyl] Cis-2,5-Dimethylpiperazine

A mixture of 25.8 g. (0.20 mole) of 3-diethylamino-1,2-epoxypropane, 12.8 g. (0.10 mole) of cis-2,5-dimethylpiperazine in 20 ml. of ethanol and 8 drops of water was allowed to stand over night at room temperature and was heated to 50° for 7 hours. On treatment with 500 ml. of water the reaction mixture tended to stay in solution. On addition of 50 g. of potassium carbonate an oil came to the surface. The oil was extracted with 150 ml. of ether. The ether layer was filtered and the ether was vacuum evaporated. On second distillation the residue yielded 16.7 g. (45% of theory) of 1,4-bis [3-diethyl-

45 A mixture of 20.3 g. of 3-(2,4-dimethylpiperidino)-1,2-epoxypropane, 8.0 g. of trans-2,5-dimethylpiperazine in 30 ml. of ethanol and 4 drops of water was allowed to stand at room temperature for two days. The reaction mixture was warmed on the water bath for about 20 hours.

On treatment of the reaction mixture with 1 liter of

60 water, an oil, mixed with solid, rose to the surface. The lower aqueous layer was discarded. The upper layer was treated with 400 ml. of ether and 1 liter of water. The aqueous layer was discarded. The upper ether layer and some undissolved solid was vacuum-evaporated to remove the ether and the residue was vacuum-distilled. The 65 yield of 1,4-bis [3-(2,4-dimethylpiperidino)-2-hydroxypropyl] trans-2,5-dimethylpiperazine, B.P. 212-213° at 0.10 mm. was 11 g.

EXAMPLE 4

1,4-Bis [3-(Di-n-Butylamino)-2-Hydroxypropyl] Piperazine

A mixture of 38.8 g. (0.20 mole) of piperazine hexahydrate in 20 ml. of alcohol and 74.4 g. (0.40 mole) of 3-(di-n-butylamino)-1,2-epoxypropane, after standing for several hours, was heated to 60° for 7 hours. The reaction mixture was treated with 1.5 l. of water and 500 ml. of ether. The ether solution was washed with 1 l. of water. Since much of the ether was lost, at this point 200 ml. of ether was added. The ether solution was evaporated and the residue was vacuum-distilled. On the second distillation the yield of 1,4-bis [3-(di-n-butylamino)-2-hydroxypropyl] piperazine, B.P. 225-228° at 0.50 mm. was 32 g. (35% of theory).

EXAMPLE 5

1,4-Bis [3-(Ethylbutylamino)-2-Hydroxypropyl]-2-Methylpiperazine

A mixture of 10 g. (0.10 mole) of 2-methylpiperazine in 30 ml. of ethanol and 32 g. (0.20 mole) of 3-(ethylbutylamino)-1,2-epoxypropane, after standing for a short time, was heated to 60° for 4 hours. The product was

25

and epihydrinamines of the structure

5 in ethanol solution and in the presence of a small amount of aqueous sodium hydroxide solution, were allowed to stand at room temperature, usually over night, and then were heated gently for about four to six hours, sometimes longer.

10 The reaction mixture was treated with water or water and alkali and the oil which came to the surface was separated, frequently by ether-extraction. The oil was subjected to fractional distillation in a vacuum.

15 In some runs a slight excess of substituted piperazine was used; in some runs the reverse was true.

EXAMPLE 7

1-[3-Morpholino-2-Hydroxypropyl]-4-[3(Di-n-Butylamino)-2-Hydroxypropyl] Cis-2,5-Dimethylpiperazine

treated with 400 ml. of water. An oily upper layer was formed when 50 g. of potassium carbonate was added. The oily layer was separated, dissolved in ether and the ether solution was filtered. On vacuum-evaporation of the ether and vacuum-distillation of the residue, the yield of 1,4-bis [3-(ethylbutylamino)-2-hydroxypropyl]-2-methylpiperazine, B.P. 199-202° at 0.30 mm., was 21.1 g. (51% of theory).

EXAMPLE 6

General Method for Preparation of Compounds of the Structure

Approximately equimolar quantities of substituted piperazines of the structure

40 To a solution of 7.5 g. (0.04 mole) of 3-(di-n-butylamino)-1,2-epoxypropane in 10 ml. of ethanol was added 2 drops of 6 N sodium hydroxide solution and 10 g. (0.04 mole) of 1-(3-morpholino-2-hydroxypropyl)cis-2,5-dimethylpiperazine in 10 ml. of ethanol. The mixture was allowed to stand for 2 days and was heated just below boiling for about 4 hours.

45 To the reaction mixture was added 125 ml. of water. Some oil separated. The amount of oil was increased by treatment with 125 ml. of 6 N sodium hydroxide solution. The oil was extracted with 100 ml. of ether. The ether was evaporated and the residue was vacuum-distilled.

50 The yield of 1-[3-(morpholino)-2-hydroxypropyl]-4-[3-(dibutylamino)-2-hydroxypropyl]cis-2,5-dimethylpiperazine, B.P. 213-214° at 0.09 mm., was 7.0 g. (39 percent of theory).

EXAMPLE 8

1-(3-Piperidino-Hydroxypropyl)-4-(3-Diethylamino-2-Hydroxypropyl)-2-Methylpiperazine

70 To a solution of 2.58 g. (0.020 mole) of 3-diethylamino-1,2-epoxypropane in 25 ml. of ethanol was added 5 ml. of 6 N sodium hydroxide solution and 6.2 g. (0.027 mole) of 1-(3-piperidino-2-hydroxypropyl)-2-methylpiperazine in 25 ml. of ethanol. After standing for a few days at room temperature the reaction mixture was heated 75 just below boiling for about 6 hours.

On treatment of the reaction mixture with 300 ml. of 6 N sodium hydroxide solution an oil separated. This oil was extracted with 100 ml. of ether. The ether layer, on vacuum-evaporation and vacuum distillation of the residue, yielded 2.4 g. (32% of theory) of 1-(3-piperidino - 2 - hydroxypropyl) - 4 - (3 - diethylamino - 2 - hydroxypropyl) - 4 - (3 - diethylamino - 2 - hydroxypropyl) - 2 - methylpiperazine, B.P. 190-191° at 0.15 mm.

Note: Likely some isomeric 1-(3-diethylamino-2-hydroxypropyl)-4-(3-piperidino-2-hydroxypropyl)-2-methylpiperazine was present, also.

EXAMPLE 9

1-[3-Morpholino-2-Hydroxypropyl]-4-[3-(2,4-Dimethylpiperidino)-2-Hydroxypropyl]Piperazine

To a solution of 6.0 g. (0.026 mole) of 3-(2,4-dimethylpiperidino)-1,2-epoxypropane in 10 ml. of ethanol was added 2 drops of 6 N sodium hydroxide solution and 6.7 g. (0.026 mole) of 1-(3-morpholino-2-hydroxypropyl)piperazine in 10 ml. of ethanol. The reaction mixture was allowed to stand for about two days and was heated just below boiling for about 4 hours.

The reaction mixture was treated with 250 ml. of 3 N sodium hydroxide solution. The oil, which separated, was dissolved in ether and was filtered. On vacuum-evaporation of the ether and vacuum-distillation of the residue there was obtained 4.5 g. (40% of theory) of 1-(3-morpholino - 2 - hydroxypropyl) - 4 - [3 - (2,4-dimethylpiperidino) - 2 - hydroxypropyl]piperazine, B.P. 222-223° at 0.10 mm.

The example given just below illustrates reactions 5 and III.

EXAMPLE 10

1-(3-Dimethylamino-2-Hydroxypropyl)-4-(3-Morpholino-2-Hydroxypropyl)Cis-2,5-Dimethylpiperazine

To 5.16 ml. (0.06 mole) of epichlorohydrin in 10 ml. of ethanol was added 1 ml. of 2 N sodium hydroxide solution. To this mixture was added slowly with stirring over a period of 1.5 hours a solution of 12.9 g. (0.053 mole) 15 of 1-(3-morpholino-2-hydroxy-propyl)cis-2,5-dimethylpiperazine, the temperature being kept below 20°. After 3 hours of stirring the reaction mixture was treated with a

solution of 4 g. of sodium hydroxide dissolved in 60 ml. of water. After 1 hour of stirring the mixture was extracted with 150 ml. of ether. To the ether solution was added 0.10 mole of dimethylamine in 25 percent aqueous 30 solution. The mixture was allowed to stand over night. The ether was vacuum-evaporated and the residue remaining was heated gently on a sand bath for about 4 hours.

The reaction mixture was treated with 125 ml. of 6 N sodium hydroxide solution. An oily layer was formed. 35 On addition of 125 ml. of water much of this oil dissolved. The amount of oily layer was increased by the addition of another 125 ml. portion of 6 N sodium hydroxide solution. The oil was extracted with 125 ml. of ether. On vacuum-evaporation of the ether and vacuum-40 distillation of the residue there was obtained 1.8 g. (10 percent of theory) of 1-(3-dimethylamino-2-hydroxy-methylpiperazine, B.P. 194-196° at 0.09 mm. pressure.

In Table I are given representative compounds of structure C, in which A, A', B and B' are varied.

^a Trans.^b cis.

Quaternization of compounds of structure C takes place readily with methyl iodide. Dimethiodides are formed by the reaction of alcoholic solutions of the alkanolamines of structure C with three molar quantities of methyl iodide at room temperature for approximately three weeks. Details are given below for the formation and isolation of a typical dimethiodide.

EXAMPLE 11

Reaction of 1,4-Bis[3-(2-Methylpiperidino)-2-Hydroxypropyl]Cis-2,5-Dimethylpiperazine with Methyl Iodide

A solution of 4.3 g. (0.01 mole) of the title alkanolamine and 4.26 g. (0.03 mole) of methyl iodide in approximately 25 ml. of ethanol was allowed to stand for about three weeks in a stoppered flask. On the addition of anhydrous ether a gum was formed. After trituration of the gum with ether it was dissolved in absolute ethanol. Again the gum was precipitated by the addition of anhydrous ether. On trituration with ether the gum solidified. The solid was filtered and dried in a vacuum desiccator. The quaternary salt thus obtained was a high melting solid, very soluble in water but not appreciably hygroscopic. Calculated for (C₂₄H₄₈N₄O₂)(CH₃I)₂: I, 36.0%. Found, 36.1%.

By the same general procedure, dimethiodides were obtained by the reaction of methyl iodide on 1,4-bis(3-dimethylamino-2-hydroxypropyl)cis-2,5-dimethylpiperazine, 1,4-bis[3-(2-methylpiperidino)-2-hydroxypropyl]-2-methylpiperazine and 1,4-bis[3-(2,4-dimethylpiperidino)-2-hydroxypropyl]cis-2,5-dimethylpiperazine. All of these products had high melting points and were very

20 soluble in water. They were on the border line as to being hygroscopic.

The dimethiodides of compounds of structure C are curare-like substances which have proved capable of complete relaxation of skeletal musculature without the production of respiratory paralysis. These compounds have 25 the advantage over many curare-like products that they are potent but transient in action.

We claim:

1. A compound selected from the group consisting of 30 compounds of the formula

and their non-toxic acid addition salts, where each of A and A' is a member chosen from the group consisting of H and CH₃ and each of B and B' is a member chosen from the group consisting of pyrrolidino, piperidino, 2-methylpiperidino, 2,4-dimethylpiperidino, morpholino and a dialkylamino radical of the structure

where each of R and R' is an alkyl radical containing from one to four carbons.

2. A compound of the formula

3. A compound of the formula

4. A compound of the formula

17

5. A compound of the formula

6. A compound of the formula

No references cited.

UNITED STATES PATENT OFFICE
CERTIFICATE OF CORRECTION

Patent No. 3,037,983

June 5, 1962

Charles F. Geschickter et al.

It is hereby certified that error appears in the above numbered patent requiring correction and that the said Letters Patent should read as corrected below.

Column 1, line 46, for "methiodies" read -- methiodides
--; column 2, line 3, for

same column 2, line 69, and column 3, lines 4, 10, 17, and 24, for A A

column 3, line 4, for

line 24, strike out "+"; line 37, for

column 5, line 60, strike out the period and insert instead a comma; column 6, line 12, for

column 6, line 41, for "3-di-n-propylamino)" read

-- 3 -(di-n-propylamino) --; column 8, line 6, for "LL 50"
 read -- LD 50 --; column 11, line 7, strike out "-4-(3-diethylamino-2-hydroxypropyl"; column 12, line 41, strike out "propyl)-4-(3-morpholino-2-hydroxypropyl)cis-2,5-di-" and insert the same after "-hydroxy-" in line 42, same column 12; column 13, TABLE I, line 1, for

same line 1, for

column 13, line 9, for

both occurrences; same column 13, line 12, for

column 15, line 1, for

same line 1, for

read

same column 15, line 3, for

read

Signed and sealed this 6th day of November 1962.
